STEAM-ELECTRIC PRESSING AND IRONING DEVICE

Merrill M. Kistner, Chicago, Ill.

Application June 5, 1940, Serial No. 338,962

16 Claims. (Cl. 38—77)

The present invention relates to improvements in fabric ironing and pressing devices and more particularly to devices of this type embodying means for steam treating fabrics during the ironing or pressing operation.

An object of the invention is to provide a new and improved device of this character which embodies means for heating the ironing base or shoe in novel association with other structural elements by which water is converted into steam and effectively superheated without appreciable time loss and with high efficiency in the use of the available heat energy.

More specifically stated, an object of the invention is to provide an ironing or pressing device embodying a rod-like electric resistance heating element arranged in a novel manner such that heat energy emanating from all sides of the element is utilized effectually in heating an ironing base or shoe below the element and in generating and superheating steam in flow passages located along the sides and above the element.

Another object is to provide a device of this nature in which steam created from an intermittent flow of water by drops will be delivered from steam discharge ports in a substantially steady stream.

Another object is to provide an ironing and pressing device embodying a new and improved structure for generating steam in which such water as may not have been instantly converted into steam is quickly translated from the area in which generation occurs in such a way that it cannot be entrained and discharged from the device in unconverted condition, in which such water is quickly converted into steam, and in which the steam from both sources is superheated.

Another object is to provide a new and improved ironing and pressing device embodying a novel relationship of a heat control thermostat to the base of the device by which accurate response of the thermostat to variations in the temperature of the base is obtained.

Still another object is to provide a device of the type set forth in which the thermostatic control device for the heating element of the iron is so related to the reservoir supplying the water for steam generation that the thermostatic device is not materially affected thermally by the presence or absence of water in the reservoir.

Another object is to provide in a pressing and ironing device novel means for establishing a connection between the electrical elements in the

device and the conductors leading from the current source to the device.

The invention also resides in various structural improvements and innovations in the device by virtue of which efficiency and simplicity of operation are combined with low manufacturing cost and ruggedness of construction, of which structural features may be particularly mentioned the improved arrangements whereby the device may be assembled in a few sections, the novel means for securing such sections together, the novel water flow control valve assembly through which the water reservoir may be filled, the improved handle assembly affording protection electrically and thermally to the electrical conductors and the improved means by which the water reservoir and the parts associated therewith are heat insulated from the ironing base or shoe.

Figure 1 is a view in side elevation of a steam-electric pressing and ironing device embodying the features of the invention.

Figure 2 is a plan view of the device on a larger scale, an intermediate portion of the handle being broken away.

Fig. 3 is a perspective view of the sole plate or ironing base, certain closure elements being illustrated in disassembled relation thereto.

Fig. 4 is a plan view of the sole plate or ironing base showing the inner face thereof.

Figs. 5, 6 and 7 are transverse views through the device taken respectively along the lines 5—5, 6—6 and 1—7 of Fig. 4.

Fig. 8 is a longitudinal sectional view through the device taken on a central vertical plane.

Pressing and ironing devices embodying the present invention have a number of features which contribute materially to the efficient operation thereof in the hands of the housewife. These features will hereinafter be more particularly discussed. The drawings illustrate an exemplary form of ironing and pressing device embodying the invention. As shown, the device, or, as it may be more conveniently termed, the iron, is fashioned in three sections herein identified as the ironing base or shoe section 20, the shell or reservoir section 21, and the handle section 22. The base section structure includes the heating element, the steam passages, and the heat control thermostat; the reservoir section structure carries the water reservoir and the water flow control valve assembly and supports the handle assembly, and the handle section assembly houses a part of the control valve assembly and embodies the means for establishing an electrical connection between the electric elements in the iron

55

and the leads from a source of current. Each of the three sections may for the most part be constructed as separate units and thereafter conveniently assembled in accordance with present day methods of economical quantity production.

The principle of the generation of steam from small quantities or drops of water successively discharged into a heated generating zone, as distinguished from the principle of steam generation in a boiler or heated reservoir, is utilized to create a supply of steam in the present device and the volume of steam is varied as required by a simple valve adjustably controlling the discharge of water to the point of steam generation. Aside from the heat control thermostat, this valve is the only movable part on the device and as a result the operation of the device does not differ in any material aspect from that of the conventional dry iron.

One important feature of the present invention is the arrangement of the heating means relative to the ironing base or shoe and to the steam chambers or passages by which arrangement the heat energy produced by the heating element is utilized substantially in its entirety for two purposes, namely, the maintenance of the ironing surface at a desired uniform ironing temperature, and the generation of steam and the maintenance thereof at an elevated or super-heated temperature until it is discharged from the base or shoe into the fabric. This efficient utilization of the heat energy minimizes the heat energy loss into the other elements of the iron.

Referring particularly to Figs. 3 and 8, the ironing base or shoe section 20 includes a generally triangularly shaped sole plate 23 having a polished flat ironing surface or bottom face 24, a pointed nose 25, and a substantially flat, transverse heel 26, the contour of the sides between the nose and the heel being arcuate as in conventional ironing devices. Peripherally the sole plate 23 is provided with upstanding side and heel flanges 27, 28, respectively (Fig. 3), constituting the side and rear walls of the base section. The sole plate, the side walls and other parts to be described may be economically formed in a single die-casting or like operation of a suitable material such as the aluminum alloy known commercially as "Lynite."

Approximately midway between the nose and heel of the sole plate is a transverse partition or wall 29 (Fig. 4) extending from side wall to side wall and having a centrally located enlargement or stud 30. The generation, flow and discharge of steam is in the present instance confined to the portion of the sole plate ahead of the partition and the heat control thermostat and electrical connections are disposed rearwardly thereof. The area ahead of the partition is hermetically sealed by a closure plate 31 (Fig. 3) seated within and slightly below the outer faces of the side walls and the partition on ledges 32 formed as lateral continuations of the walls and partition. The closure plate may be secured to the ledges in any suitable manner as by a press fit.

Superimposed upon the base and in intimate heat exchange relation therewith is the heating element 35. This element is, in the present embodiment, of the type characterized by being of elongated cylindrical or rod-like form and structurally comprises, as shown in Fig. 8, a resistance wire 36 embedded in a heat conductive dielectric material 37 which, in turn, is encased by a protective metallic sheath 38. The heating element is utilized not only as a combined sole plate heat-

ing and steam generating means but as a means defining part of the steam flow passages as well. To this end, the element is so related to the sole plate that it projects or extends rib-like beyond or above the upper inner surface of the sole plate within the confines of the side walls 27, 28. A number of methods of so assembling the element on the sole plate may be satisfactorily employed but it is preferred to obtain an intimate and highly efficient heat exchange relation between the element and the sole plate by casting the heating element within a comparatively thin layer or case 39 (Figs. 5 and 6) of the aluminum alloy. The encased element thereby forms a highly heated rib on the upper or inner surface of the sole plate.

As may be seen in Fig. 4, the heating element in the present instance is a continuous member of generally U-shaped configuration having spaced legs 40 connected by a closed end portion 41. Toward the closed end portion, the legs may be offset inwardly or toward each other, as indicated at 42, so that the element follows generally the contour of the side walls from the heel to the nose and return and, functionally, provides a nose portion which encloses with live heat radiating surfaces three sides of a restricted area 43. The dimensions of the element locate it in inwardly spaced relation to the side walls 27, 28 and, depending on the unit heat energy output thereof, in such relation to the mass of metal in the sole plate as to insure a substantially uniform distribution of heat over the ironing surface 24. The restricted area 43, being substantially encircled by the heating element and being defined by parts having a relatively small metal mass, will initially reach its maximum temperature more quickly than other areas of the sole plate and its comparative temperature will be somewhat higher. This area, as will become apparent, is the zone in which steam generation occurs.

The rear limit of the restricted area 43 is indefinite since the entire space between the heating element legs is open to the partition 29 but, given a proper correlation between water input and available heat energy, steam generation will occur primarily in the space rather closely adjoining the extreme nose of the heating element. The space just ahead of the partition is enlarged, as at 48, because of the offset 42 of the heating element and in this space occurs the expansion and initial superheating of the steam first generated and the conversion into steam of any remaining fluid particles. The inner surface of the base slopes downwardly and rearwardly, as indicated at 49, through the steam generation zone 43 and chamber 48 and is transversely crowned or convex so that any water dropping into the generation zone and not instantly converted into steam will be transversely directed and will pass out of said zone along the highly heated inner surfaces of the heating ribs.

As may best be seen in Fig. 4, the central stud 30 extends forwardly into the chamber 48 below the closure plate 31 and is fashioned to divide the rearmost portion of said chamber into two branches 51 each following a leg of the heating element. Preferably, a series of walls 52 extend vertically between the closure plate and the base and transversely into the inner chamber from the heating ribs. These walls may be formed integrally with the base and ribs and are arranged in alternate or staggered relation. The inner or free ends of the walls extend past the longitudinal center line of the base and the walls angle

toward the generating zone or are slightly concave in that direction to provide pockets 53 between the walls and ribs which face forwardly to catch such water as might not be converted into steam. The path of steam flow past the walls is circuitous and, since the walls are at approximately the temperature of the heating ribs, any entrained water particles will be converted into steam. Should water tend to accumulate on the base it will flow rearwardly of the chamber from pocket to pocket until it is wholly converted into steam.

The nose portion of the heating element encasing rib ahead of the partition has on its upper surface spaced, parallel flanges 54 extending substantially the length of said portion and defining therebetween a groove 55 which is closed by the closure plate 51 when said plate is sealed to the base to form a steam channel. If desired, the depth of the groove may be increased by providing a registering groove 56 in the opposing surface of the closure plate. Each end of the steam channel on the rib communicates through a port 57 in the inner one of the flanges 54 with a branch 51 of chamber 48.

Between the outer faces of the heating rib and the side walls and ledges opposed thereto is a steam distributing chamber divided, in this instance, into a nose section 58 and two side sections 59 by webs 60 extending between the heating rib 39 and the side walls toward the nose portion of the base. At spaced intervals the ledges have side recesses 61 providing shoulders 61' (Fig. 5) above the base of the chambers 58, 59 and steam discharge ports 62 extend through the shoulders to the ironing surface 24. Communication between the groove 55 and the side distributing chambers 59 is obtained through ports 63 in the flanges 54 and between the groove and the nose distributing chamber 58 through a pair of spaced ports 64. Better equalization of steam distribution in the nose chamber is obtained if two ports 64 are provided. The creation of an excessive or undesirable amount of steam pressure in the steam flow passages is avoided. Thus, the total cross-sectional area of the ports 57 is of sufficient size to pass the maximum volume of steam that will be generated under operating conditions. The total cross sectional areas of the ports 63, 64 and of the ports 62 are no smaller than the area of ports 67 and preferably each area is slightly greater than the area of the ports next in advance thereof.

As may be seen in Fig. 8, the steam generating area 48 is surmounted by a tubular boss 65 cast integrally with the heating rib 39 just rearwardly of the nose bend thereof and the boss is arranged to extend upwardly through the closure plate 51 to a point slightly above the top plane of the side walls. The rear portion of the boss is integral with a narrow wall 66 extending between the opposed portions of the heating rib in spaced relation to the base surface 48. The boss is internally screw threaded. If desired, small passages 66a may be formed in the boss 65 connecting the groove 55 and the generating zone (see Figs. 4 and 8). These passages may be directed toward the path of the drops of water falling into the generating zone through the boss 65. In operation these ports tend to smooth out pulsations in the flow of steam.

Centrally of the sole plate behind the stud 38 is a well 67 laterally defined by spaced upstanding walls 68. Rearwardly sloping transverse walls 69 connect the walls 68 with the side walls 21

near, but in spaced relation to, the heel wall 28. The encased legs of the heating element pass through the spaces 18 enclosed in part by the walls 68, 69 and the opposite ends of the bare heating element extend rearwardly through the walls 68 and terminate in upturned end portions 71 from which terminals 72 connected with the resistance element 36 project. The electrical connections from the terminals 72 are not shown for the sake of simplifying the drawings. Plates 73 may, if desired, be provided to close the spaces 18 which plates may be secured in place in the same manner as the closure plate 51.

A heat control thermostat 74 may be of any suitable conventional construction and, since it per se forms no part of the invention, will not be specifically described. It is preferred, however, to employ a thermostat having certain characteristics found to be desirable. Thus, it is preferred that the thermostat be one in which bimetallic thermal elements respond primarily to heat conducted thereto through the frame parts of the thermostat. Such frame parts are designated 75 (Fig. 8) and one part is arranged to be secured as by screws 76 to the upper face of the stud 38. This face has a rearward slope so that the thermostat unit extends rearwardly and downwardly into the well 67 and is maintained in substantially evenly spaced relation to the several elements of the base. An adjusting screw 77, operable in the usual manner to adjust the thermostat for control movement at different temperatures, extends away from the sole plate in assembly and carries an actuating finger piece 78.

The water reservoir is located within the shell section 21 of the device and is so constructed and arranged therein that the overall dimensions of the present iron are substantially the same as those of conventional dry irons. The shell section is arranged to be separately assembled into a complete unit before it is secured to the previously assembled base or shoe section and is so constructed as to provide a minimum area of metal to metal contact with the ironing shoe section whereby to reduce materially conduction of heat to the water in the reservoir.

The shell or reservoir section 21 includes an outer shell or wall 79 preferably fashioned as a drawn aluminum piece which is relatively deep at the nose and diminishes in height toward the heel. The margin of the shell is shaped substantially to follow the contour of the side walls 21 of the shoe and in assembly to continue the outer surface of said side walls. However, the shell is so dimensioned that the heel or rear portion thereof extends somewhat beyond the heel wall 28 on the shoe as shown in Fig. 8. It is preferred that, except at the extreme nose and heel portions of the iron, an air gap 80 be provided between the shell and the side walls 21, and in this instance the gap is obtained by cutting away the upper margin of the side walls 21 as indicated at 81 (Fig. 3). This air gap minimizes heat conduction between the shoe and the shell.

Cooperating with the shell to form a water reservoir is a flat sealing plate 82 (Fig. 8) secured as by welding through flanges 83 to the shell 79 near the margin thereof and having a rear wall 84 extending to the inner top surface of the shell and there similarly secured. The flat portion of the sealing plate is, however, spaced a substantial distance from the upper surface of the shoe assembly to reduce the transfer of heat from the shoe to the sealing plate. The assembly of the

shell and sealing plate defines a water reservoir 85 of substantial capacity. The thermostat adjusting screw 77 extends through the top wall of the shell 79 rearwardly of the reservoir.

The assembly of the base and reservoir sections is effected in the present instance by means which allows of independent thermal expansion and contraction of the base section relative to the reservoir section. Within the shell heel wall 90 (Fig. 8), a block 91 is fixed to extend toward but not to the opposing or external surface of the base heel wall 28. The inner side of the latter has enlargements 92 (Figs. 3 and 8) and headless screws 93 engaging the block 91 and extending into aligned bores in the enlargements 92 secure the heel portions of the reservoir and base assemblies together for limited movement in the plane of the base.

The reservoir and base sections are in the present embodiment connected at the nose end of the iron by means which forms a part of the valve assembly for controlling the flow of water from the reservoir. As may be best seen in Fig. 8, the internally screw threaded boss 85 on the base receives a nipple 94 having an external radial flange 95 arranged to seat against the axial face of the boss 65. In axial alignment with the nipple 94 and boss 85, is an aperture 96 in the flat sealing plate 82 of the reservoir section. This aperture is defined by a flange 97 which is internally screw threaded to receive a disk 98 provided with an axial aperture 99 of the same internal diameter as that of the nipple. The aperture and the nipple have continuing screw threads for engagement by a tubular member 100 which serves as a connecting means between the reservoir section and the base section. The end of the member 100 within the nipple is closed except for a restricted axial port 101 through which water may discharge from the reservoir 85 onto the base surface 49 in the steam generating zone 43. The end wall of the tubular member 100 is fashioned as a seat for a needle valve 102 by which the rapidity of water discharged through the port 101 is variably controlled. The needle valve 102 forms part of a valve assembly, designated generally 103.

Delivery of water from the reservoir is at a rate of flow optionally variable between no flow (in which condition the iron may be used as a dry iron) and a flow that will result in the generation of a volume of steam sufficient for any ironing purpose. The valve is capable of instant manipulation to any desired setting and these settings are calibrated to meet the steam requirements for fabrics of various types. The relationship of the valve and the discharge port which it controls to the iron as a whole is utilized to achieve an important feature of the present structure. Thus, the valve assembly is so constructed that it provides the opening through which the reservoir is filled and the arrangement is such that the quantity of water that may be placed in the reservoir is definitely limited to a predetermined maximum. The valve controlled opening through which water is discharged to the steam generator is so located on the reservoir that when the iron device is up-ended to an idle position in which the iron body is resting on its heel, the valve controlled opening is always above water level. Consequently, the mere act of up-ending the iron produces an instant cessation of steam generation.

The valve assembly 103 extends through the water reservoir 85 and the external end thereof 75

is concealed and in part supported by the front end of the handle section 22. The handle section is preferably formed of a dielectric molded plastic material and includes a generally horizontal hand portion 104 and front and rear standards 105 and 106, respectively. The rear standard is secured to the upper surface of the shell by such means as screws 107. The front standard 105 is somewhat enlarged and is provided with a bore 108 in substantial axial alignment with the boss 65 on the base section. The upper wall of the shell 79 has an opening 109 therein also in such axial alignment. A flanged bushing 110 projects through the opening 109 into the bore 108 with the flange thereon seated against the inner surface of the shell 79. The end of the bushing within the bore 108 is externally screw threaded to receive a nut 111 which bears against a shoulder 112 facing outwardly in the bore 108. This arrangement secures the front standard of the handle section to the reservoir section.

The bushing 110 is internally screw threaded throughout its length for engagement by external screw threads on a tubular stem 113. In assembly, the stem extends substantially through the reservoir 85 and a tubular nut 114 threaded into the inner end of the stem has an end socket 115 to receive a ball 116 on the end of the stem of the needle valve 102. A plug 117 threaded into the nut 114 closes the socket 115 to provide limited but ample play to enable the needle valve to center itself with respect to its valve seat. The outer end of the stem 113 has a head 118 providing with the adjacent end of the bushing and nut 111 a groove to receive a collar 119. The collar has a series of spring legs 120 extending outwardly in a direction parallel to the axis of the assembly. Near their extremities, each leg is provided with a nib for engagement in an annular groove 121 formed in the external surface of the shank of a valve manipulating head 122. The shank fits snugly about the head 118 of the stem and the parts are detachably secured together in any suitable manner for joint rotational movement as by providing interfitting serrations on the abutting surfaces thereof. The outer face of the head 122 is preferably flush with the upper face of the standard 105 and beyond the shank the head is enlarged to a diameter that, as shown in Figs. 1 and 2, disposes the side portions of the head slightly beyond the sides of the front standard. This arrangement enables an operator to conveniently turn the head and effect an adjustment of the valve 102. Preferably, the outer face of the head carries a series of indicia 123 for designating the various settings of the valve.

As shown in Figs. 2 and 8, the head 122 is provided with an enlarged passageway 124 having an outwardly flaring funnel shape and communicating with the bore 125 through the stem 113. At its lower end the stem has axially parallel slots 126 therein to permit water poured into the passageway 124 to pass into the reservoir 85. A ball 127 loosely disposed in the slotted end of the stem 113 is arranged, when the iron is up-ended, to seat against an inwardly facing shoulder 128 on the stem and prevent a possible flow from the reservoir of such water as might be trapped in the stem when the iron is up-ended. A short tubular air duct 129 extends through the upper wall of the shell 79 adjacent to the nose portion thereof as a vent for the escape of air from the reservoir as it is filled. The front handle standard 105 includes means for facilitating such es-

cape of air which, in the present structure, includes an internal recess 130 into which the duct 129 opens, a communicating slot 131 in the standard along the bushing 110 and clearance between the standard bore 108 and the nut 111 and manipulating head 122.

It will be noted that the mouth of the air escape duct 129 within the reservoir 84 determines the maximum quantity of water that may be poured into the reservoir through the passages in the valve assembly since the air entrapped in the upper portion of the reservoir, when the water level rises above the inner end of the duct, prevents further entrance of water. The volume of air that will thus be trapped in the filled reservoir is predetermined to be that volume which, when the iron is up-ended, occupies the nose portion of the reservoir and locates the water level below the outlet port 101.

It may be noted, by reference to Fig. 8, that when the iron is up-ended to an idle position in which it is supported by the wall 90 of the shell and by a rearwardly projecting nib 132 at the upper end of the rear standard, the iron is tilted past a vertical plane. This arrangement has the effect of raising the outlet port 101 with respect to the water level in a filled reservoir and increases the available capacity of the reservoir.

Another structural feature is embodied in the means by which current is conducted to the thermostat and heating element of the device. The arrangement is such that a quickly accessible connection between the flexible current conductors leading to the iron and the conductors leading from the operating elements in the iron is established at a point well remote from the heated portions of the device. In this instance, such connection is made on the handle of the iron a substantial distance from the upper surface of the iron body or shell. The arrangement moreover utilizes the dielectric property of the handle material to electrically and thermally insulate bare leads or conductors from the operating elements of the device.

This feature and one structural embodiment thereof is particularly described and claimed in my Patent No. 2,308,515, issued January 9, 1943, and reference thereto may be had for a more detailed description thereof. For present purposes the arrangement may be briefly described as follows: The handle standard 106 has a rearwardly opening socket 135 therein to receive a plug 136 complementary to the socket and the outer surfaces of the standard. The electrical connections from the thermostat and the heating element are exemplified by the lead 137 and extend from the body of the iron into the socket. These leads and other leads 138 (which extend through a cable or cord 139 to a source of power) are respectively connected with suitable detachably engageable prongs and sockets, indicated at 140, for establishing the circuit. The plug 136 may, if desired, be held in place by such means as screws 141.

A further feature of the invention is the provision of correlating indicia in association with the control elements of the heat regulator and the water valve whereby for any given fabric settings producing a proper ironing temperature and a proper volume of generated steam may be instantly derived. This feature is eminently desirable because of the fact that the household laundry of today includes, in addition to woolen, linen, cotton and silk fabrics, various types of fabrics fashioned of synthetic materials as well

as various mixtures of natural and synthetic materials. For each of these many materials, there is a proper ironing temperature. Likewise, each fabric will respond best when subjected to a quantity of steam found to be proper for that fabric. It has been discovered that when any fabric is ironed and steamed at its proper temperature and with its proper quantity of steam, the fabric is in effect rejuvenated; that is to say, the fabric substantially regains the texture, resiliency and appearance it had when it first came from the loom. Since such a result is best obtained when the temperature and quantity of steam are substantially at their proper values, the correlating indicia by which the housewife may instantly set the iron to obtain such operating conditions becomes an important factor in enabling most effective operation of the device.

With reference to Fig. 2, the thermostat controlling finger piece 18 is encircled by a plate 165 bearing suitable words or indicia 166 indicating generally the several broad ranges of temperature control, for example, "Off," "Low," "Medium" and "High." The plate 165 also carries other indicia or symbols 167 designating a low temperature range within which the iron will function only as a dry iron, the available heat energy within this range being insufficient to generate steam. The upper surface of the shell 79 carries a third series of indicia 168, each subdivision of which designates a temperature range and the identity of the particular types of fabric most effectively ironed within the designated range. Correlated with the fabric designations are other indicia, for example numerals, which correspond with the indicia 123 on the valve manipulating head 122. This relationship of the fabric designating indicia and the valve setting indicia is determinative of the coordinated settings of the temperature control thermostat and the water control valve for any fabric and enables the user to obtain quickly and efficiently the proper ironing temperature and the proper volume of steam for any type of fabric.

In considering the operation of the device, it will be presumed that the user has first filled the reservoir, as by holding the opening in the head 122 under a faucet, that the iron is connected with a source of current and that the thermostat is turned to its "Off" position and the valve to its closed position. The user having determined the character of the fabric to be ironed adjusts the thermostat to the proper temperature range as determined by the fabric identifying indicia 168 and opens the valve by manipulation of the head 122 to the setting indicated by the same indicia. Because of the effective association of the heating element with the base, the ironing surface reaches its predetermined operating temperature quite rapidly so that no appreciable delay is required between the time the iron starts to heat and the time the water valve is opened.

As water discharges through the port 101, it drops onto the surface 43 in the highly heated steam generating zone 49 where much if not all, of the water is converted into steam. The steam thus generated, together with unconverted water particles, passes rearwardly into the adjoining chamber in which initial superheating of the steam occurs. Any water particles moving out of the generating zone along the inclined and crowned base surface will tend to travel along the highly heated channels at the bottoms of the heating ribs while being constantly subjected to heat. Water particles entrained in the steam

will be converted during the circuitous travel of the steam past the inwardly projecting walls 52. In the event of an unusual excess of water, the pockets 53 will trap and check a rearward flow thereof and the wall arrangement will cause any overflow from one pocket to traverse the base surface to the next pocket on the opposite side of the chamber. Since the water movements are across and past heated surfaces, continuous steam generation will occur.

From the inner chamber the steam passes through the ports 57 into the groove 55 on the upper surface of the heating rib and thence into the steam distributing chambers 58 and 59 from which it is discharged into the fabric through the ports 62. It will be noted that as the steam flows from the generation zone, it passes first along the inner sides of the heating rib, thence along the upper surface of the heating rib, and finally into chambers adjoining the outer surfaces of the heating rib. Thus, the heat energy available on all of the sides of the heating rib is most effectively utilized, the lower side for heating the base, and the lateral and top sides for generating steam and superheating it. The continuous expansion of the steam following its generation, as well as the circuitous path of its travel, smooth out and substantially eliminate the pulsations caused by the generation of steam from intermittently delivered drops of water.

As long as the user does not change the type of fabric being ironed so that a new setting of the thermostat and valve is required, it is unnecessary to pay further attention to the adjustment controls. During the momentary intervals when the iron is idle, the user merely up-ends the iron in the conventional manner so that it rests upon its heel. Since in this position the water level in the reservoir is below the open valve port 101, the up-ending operation discontinues further delivery of water to the steam generating area. When the iron is returned to its operative position, water again starts to flow at the previous rate through the port 101 with the resulting delivery of steam without appreciable delay. To iron a type of fabric requiring different conditions of ironing temperature and steam, the user merely changes the setting of the thermostat by movement of the finger piece 78 to the new position indicated and correlates the steam value therewith by setting the valve to the designated position. Should the user wish to discontinue the generation of steam, the valve control head is turned to close the valve. The iron then performs as a conventional dry iron.

The air space between the reservoir and the adjacent surface of the base section, together with the air gap 80 between the margins of the reservoir section and the base section and the comparatively small areas of metal contact between the base section and the reservoir section, all minimize the transfer of heat energy to the water in the reservoir and prevent heating of the water therein to its boiling point. Pressure, however, cannot increase within the reservoir because of the open air duct 129 and the open stem of the valve assembly.

It may be mentioned that by the construction of the base plate herein illustrated, an iron of relatively light weight is obtained. The weight of the iron, if desired, may be increased without impairing any of the features of the invention by increasing the thickness of the base metal through the chambers 58, 59 and 70.

While the invention is susceptible of various

modifications and alternative constructions, I have shown in the drawings and have herein described in detail the preferred embodiment, but it is to be understood that I do not thereby intend to limit the invention to the specific form disclosed, but intend to cover all modifications and alternative constructions falling within the spirit and scope of the invention as expressed in the appended claims.

10 I claim as my invention:

1. In an iron of the character described, a shoe assembly having, in combination, an ironing plate, a heating means on the upper surface of said plate thermally united therewith, said means projecting above said surface and having lateral inner and outer thermal faces and an upper thermal face, and means secured to said plate providing steam flow passages connected in substantially end to end relation and defined in part by said thermal faces.

15 2. In an iron of the character described, a shoe assembly having, in combination, an ironing plate, a heating means on the upper surface of said plate thermally united therewith, said means projecting above said surface and presenting side thermal faces and a top thermal face, means secured to said plate in overlying relation to the projecting part of said heating means, and means defining communicating passages for the flow of

20 30 steam successively along the outer surfaces presented by the side, the top and the other side of said heating means.

3. In an iron of the character described, a shoe assembly having, in combination, an ironing plate having a nose portion, an elongated heating heating element secured to said plate in thermal conductive relation thereto, said element having a reverse bend portion located at the nose of the plate and substantially enclosing a restricted heated area and having continuing end portions extending along the opposite side margins of the plate, said plate having steam discharge ports opening through the ironing face thereof, means for discharging water into the substantially enclosed area, and means for defining paths of steam flow from said restricted area extending first rearwardly centrally of said plate between said end portions, then forwardly along the upper surfaces of both end portions and into communication with said ports on the outer side of said heating element.

4. In an iron of the character described, a shoe assembly having, in combination, an ironing plate having a nose, an elongated heating element secured to said plate in thermal conductive relation thereto, said element having a reverse bend portion located at the nose of the plate and substantially enclosing a restricted highly heated area and having continuing portions extending rearwardly toward the heel of the ironing plate, means for delivering water to said area, said plate having steam discharge ports opening through the ironing face thereof, and means cooperating with said heating element to define a centrally located passage for conducting steam rearwardly and a pair of channels communicating with said passage for conducting steam forwardly along the said continuing portions and into communication with said ports.

5. In an iron of the character described, a shoe assembly having, in combination, an ironing plate having a nose, an elongated heating element shaped to conform generally to the marginal outline of said plate and secured to said plate in thermally conductive relation thereto, said ele

ment projecting as a rib on the upper surface of said plate and having a reverse bend portion located at the nose of the plate and substantially enclosing a restricted area, water delivering means communicating with said area, said plate having steam discharge ports opening through the lower face thereof, and means for conducting steam generated in said highly heated area to said ports through a flow path which passes along and over the rib.

6. In an iron of the character described, a shoe assembly having, in combination, an ironing plate having a nose, an elongated heating element shaped to conform generally to the marginal outline of said plate, means for securing said element to said plate in thermally conductive relation thereto and with the upper portion of said element disposed as a rib above the upper surface of said plate, said element having a reverse bend portion located at the nose of the plate and substantially enclosing a restricted area, means for discharging water in a succession of drops into said area, the bottom surface of said plate in the enclosed area being shaped to conduct unconverted water particles away from the point of water delivery, means for retarding such water movement, said plate having steam discharge ports opening through the ironing face thereof, and means defining passages for conducting steam generated in said area to said ports including a flow passage which follows said rib.

7. In an iron, the combination of a pressing shoe having an elongated electric resistance heating element of V-shaped outline thereon, a water reservoir fixed in position on the upper side of said shoe, means for delivering water in a controlled flow from the reservoir onto a portion of the shoe bounded by the point of the heating element, the surface of the shoe within the confines of said element having a gentle slope from the point of steam generation, upstanding integral walls on the shoe bordering the sides and rear end of the sloped surface, the side walls being heated by said element, means for directing any water flow across the sloped surface into channels along the side walls, means for directing steam onto a fabric beneath the shoe, and means defining a passage to said last named means from the chamber defined by said walls on the shoe at a point remote from the point of the heating element.

8. In an iron, the combination of a generally flat cast metal pressing shoe, an elongated electric resistance heating element partially embedded in the top of said shoe and upstanding therefrom to heat the shoe by heat emanating from the lower side of the element, means for generating steam at a point adjacent the upper surface of the shoe, means for emitting the steam onto material beneath the shoe, and means for directing the steam from said generating point to said emission means along a tortuous path passing over both the lateral and top sides of said element generally longitudinally thereof.

9. In an iron, in combination, a base assembly having a substantially open interior and a pressing shoe, means including an elongated electric resistance heating element extending through said interior in heat exchange relation with the shoe for heating the pressing face thereof, said shoe having steam chambers on opposite lateral sides of said element, means for delivering water to one of said chambers, means for conducting steam generated therein to the other of said

chambers including a steam passageway along the top surface of the heating element, and means for discharging steam from the last mentioned chambers onto an article being treated.

10. A combined steam and electric iron having, in combination, an ironing shoe having a plurality of steam discharge ports through which steam may be discharged against an article being ironed, a heating element thermally united with said shoe, means defining a steam generating chamber in the nose portion of said shoe in communication with said ports, an upstanding wall of substantial mass at the rear of said steam generating chamber, a thermo-responsive control device for said element supported from said wall rearwardly of said steam generating chamber, a body section secured to said shoe in superimposed relation thereto, means providing a reservoir for water in the nose portion of said body section to occupy a position above said steam generating chamber, said reservoir being substantially thermally unrelated to said heating element, and means for controllably discharging water from said reservoir into said steam generating chamber, said body rearwardly of said reservoir and said wall having a substantially unobstructed interior to receive the upper portion of said thermally responsive element.

11. In a steam-electric ironing device, the combination of a water reservoir, an ironing shoe having heating means thereon defining a chamber, means for delivering water from said reservoir to one area in said chamber in a succession of drops, means for conducting such water as is not rapidly converted into steam away from such area, the conducting means being in intimate heat exchange association with said heating means, and means for retarding the movement of such water away from such area.

12. In a shoe assembly for an iron of the character described, the combination of a metal shoe having a heating element enclosed by the metal of the shoe, the metal which encloses said element being relatively thin and providing a top thermal face and a side thermal face directed inwardly toward the central portion of the shoe, and means mounted on said shoe in cooperative relation to said top and side thermal faces for defining therewith communicating steam passages along said side and top.

13. In an iron of the character described, a shoe assembly having, in combination, an ironing plate, heating means on the upper surface of said plate thermally united therewith, said means having a side thermal face directed inwardly toward the center of said plate and an upwardly directed thermal face, and closure means on said plate cooperating with said side and top thermal faces to provide communicating steam flow passages along said faces, said plate having steam discharge ports in communication with the steam flow passage on the top thermal face.

14. In an iron of the character described, a shoe assembly having, in combination, a metal ironing base, heating means on the upper side of said base, there being a thin wall of metal integrally united with the base and enclosing at least the upper surface of said element and the lateral surface thereof facing toward the central portion of the base whereby to provide inside and top thermal faces on said base, and means secured to said base in overlying relation to the upper surface thereof and cooperatively related to said thermal faces to define communicating passages for the flow of

steam along said faces, said base having steam discharge passages therein located between said heating means and the margin of said base and communicating with the steam passage on said top thermal face.

15. In a shoe assembly for an iron of the character described, the combination of a shoe plate having a nose portion, said nose portion having a central area providing a zone for water reception and steam generation, a sheath-type heating element laterally surrounding the nose portion of said area and extending rearwardly therefrom along the margins of the plate, said heating element being integrally united with said plate and extending above the base of said area, and means cooperating with said plate to direct the flow of steam generated in said zone rearwardly within the confines of the area enclosed by said heating element.

16. In a shoe assembly for an iron of the character described, the combination of a shoe plate having a nose portion, said nose portion having a central area providing a zone for water reception and steam generation, a sheath-type heating element laterally surrounding the nose portion of said area and extending rearwardly therefrom along the margins of the plate, said heating element being integrally united with said plate and extending above the base of said area, and means cooperating with said plate to direct the flow of steam generated in said zone rearwardly within the confines of the area enclosed by said heating element, said means and heating element cooperating to define communicating return passages along said heating element on both lateral sides of said shoe plate.

steam along said faces, said base having steam discharge passages therein located between said heating means and the margin of said base and communicating with the steam passage on said top thermal face.

15. In a shoe assembly for an iron of the character described, the combination of a shoe plate having a nose portion, said nose portion having a central area providing a zone for water reception and steam generation, a sheath-type heating element laterally surrounding the nose portion of said area and extending rearwardly therefrom along the margins of the plate, said heating element being integrally united with said plate and extending above the base of said area, and means cooperating with said plate to direct the flow of steam generated in said zone rearwardly within the confines of the area enclosed by said heating element.

16. In a shoe assembly for an iron of the character described, the combination of a shoe plate having a nose portion, said nose portion having a central area providing a zone for water reception and steam generation, a sheath-type heating element laterally surrounding the nose portion of said area and extending rearwardly therefrom along the margins of the plate, said heating element being integrally united with said plate and extending above the base of said area, and means cooperating with said plate to direct the flow of steam generated in said zone rearwardly within the confines of the area enclosed by said heating element, said means and heating element cooperating to define communicating return passages along said heating element on both lateral sides of said shoe plate.
